(57) **CLAIM**

The ornamental design for the wireless vertical enclosure, as shown and described.

DESCRIPTION

FIG. 1 is a perspective view, from the front and above, of a first embodiment of a wireless vertical enclosure showing our new design.

FIG. 2 is a left side view thereof.

FIG. 3 is a right side view thereof.

FIG. 4 is a front view thereof.

FIG. 5 is a rear view thereof.

FIG. 6 is a top view thereof; and,

FIG. 7 is a bottom view thereof.

The broken lines shown in FIGS. 5 and 7 represent environmental subject matter and form no part of the claimed design.
